Term of patent 14 years

(Cl. D4—3)

Fig. 1

Fig. 2

Fig. 4

Fig. 1 is a front elevational view of a shelf for shaving gear or the like embodying my new design;

Fig. 2 is a top plan view thereof;

Fig. 3 is a side elevational view thereof; and

Fig. 4 is a fragmentary perspective view of one end thereof.

The shelf is shown broken away in Figs. 1 and 2 to indicate indetermined length.

The essential features of my design reside in the portions shown in full lines.

I claim:

The ornamental design for a shelf for shaving gear or the like, substantially as shown and described.
